UNITED STATES PATENT OFFICE.

GEORGE T. BATES, OF ELGIN, ILLINOIS, ASSIGNOR TO ILLINOIS WATCH CASE COMPANY, OF ELGIN, ILLINOIS, A CORPORATION OF ILLINOIS.

VANITY CASE.

Application filed May 4, 1925. Serial No. 27,626.

To all whom it may concern:

Be it known that I, GEORGE T. BATES, a citizen of the United States, residing at Elgin, in the county of Kane and State of Illinois, have invented certain new and useful Improvements in Vanity Cases, of which the following is a specification.

This invention which relates to a vanity case is concerned particularly with a novel arrangement and construction of its various parts which are designed for the accommodation of certain toilet accessories. In the accomplishment of this purpose, the case is provided with suitable compartments where-
in may be retained such articles as a lip stick, rouge compact, loose facial powder, a mirror, and puffs for applying both the rouge and powder. The nature or kind of the particular cosmetics which the case retains may, of course, be varied widely.

An exemplification of my invention in its preferred form is illustrated in the accompanying drawing in the manner following:

Figure 1 is a plan view of the case as it appears when open, the cover being shown in perspective;

Fig. 2 is a similar view with the rouge and powder retainers moved to a position for the exposure of these cosmetics;

Fig. 3 is an enlarged transverse section taken centrally through the case; and

Fig. 4 is a view in plan of the rear or under side of the frame which fits into the case.

I have shown in the drawing a case A which is preferably thin, its side walls 5 being circular and upstanding from a bottom 6. To the side walls of the case is hinged a cover B upon the inner side of which is mounted a mirror 7 which may be held in place by a ring 8 which is inwardly extended from the cover side walls 9. Any suitable catch 10 may be employed to hold the cover releasably in closed position upon the case.

Fitted within the case is a frame C preferably of sheet metal, comprising a top plate 11 from which depend marginal side walls 12 which fit closely within the walls of the case. The mounting of this top plate within the case is such that it lies in spaced relation to both the cover and the case bottom. The top plate is inwardly depressed at one point to form an elongated pocket 13 in which may be accommodated some such arti-

cle as a lip stick 14. In proximity to this recess are two pockets comprising, by preference, a pair of circular cups 15 and 16. One of these cups 15, in which may be placed a rouge compact 17, is desirably secured 60 fixedly to the frame, but the other cup 16 may be removably held within a strap support 18 which depends from the under side of the top plate. In order to facilitate removal of this latter cup I provide a pair 65 of clips 19 which extend inwardly from points adjacent the upper edges of its walls. These clips serve additionally to retain in place a puff 20 which may be of such shape and size as to be receivable within this cup. 70

A closure for the fixed cup is also provided, the same comprising a generally circular lid 21 having a laterally extending finger 22. A pin 23 serves to pivotally connect the lid to the case. A lid answering 75 to this description may be positioned directly over the pocket 15, as shown in Fig. 1, or be shifted laterally to the position of Fig. 2 so as to expose the rouge therewithin. In the normal position of Fig. 1, the finger 22 80 projects over the pocket 13 so as to confine in place the lip stick 14 which is there kept. This finger accordingly acts as a retaining clip which may be shifted to one side whenever the lid is swung around to uncover the 85 rouge pocket.

Except for the three pockets already noted, all of which extend inwardly of the top plate, the entire space within the frame is unoccupied. This forms a compartment of 90 appreciable size in which may be received a quantity of loose facial powder. This powder may be readily introduced into this compartment by taking out the removable cup 16. In order that this powder may be 95 available for use I provide means as follows:

In the top plate I may provide a very slight depression 24 extending over that portion of its surface which is proximate to the sides of the two cups that are remote from the pocket 13. Such a depression has a contour consisting of two concave sides, closely adjacent the walls of the cups and one convex side adjacent the periphery of the top plate. Within this depressed portion of the plate are a plurality of slots 25, six being the number shown. These may be desirably arranged in two groups of three each. Formed to lie within this depre- 110

sion of the top plate is a sifter lid 26 having a pivotal connection 27 therewith at a point which is close to the two cups and equidistantly from each other. This lid 26 has capacity for a limited swinging movement within the depression 24 wherein it is accommodated, and is provided with a plurality of slots 28 adapted to register with the plate slots 25 when the lid is moved laterally to one extreme position. The powder which is stored beneath the top plate may accordingly escape through these openings when the parts are related as shown in Fig. 2. If, however, the lid be moved to an opposite position, as shown in Fig. 1, the openings 25 in the top plate are closed with the result that further escape of powder is prevented. At the opposite ends of the lid are provided upstanding lugs 29 which may be readily engaged by the finger to facilitate shifting of the lid. It may be noted that this lid need execute only a slight movement in order to open or cover the openings 25, and that its extreme positions are determined by engagement with the margins of the depression 24, as best indicated in Fig. 1.

With a case of the kind described, I may also associate a powder puff 30, the same being receivable between the top plate and the cover. Such a puff may have a diameter the full width of the case. I am accordingly able in the present case to provide both a powder puff and a mirror of maximum size, also capacity for a very considerable quantity of loose powder, the same being readily releasable without disturbing the positions of any other parts. The case may be used without any concern as to its contents becoming disarranged or working loose, regardless of whether or not the cover be opened, for the reason that the articles carried therein are all secured in place through the instrumentality of very simple devices.

I claim:

1. A vanity case having a bottom and marginal walls within which is fitted a frame having a top plate whereby to define a compartment suitable for loose material, a pair of pockets depending from the top plate into said compartment each adapted to receive an article, a lid slidably mounted upon the top plate adapted in one position to close one pocket, and to present a portion of itself in overlying relation to the other pocket whereby to confine an article therewithin, and sifter means movable independently of the lid for controlling the discharge of loose material from the compartment, substantially as described.

2. A vanity case having a bottom and providing a mounting for a transversely extending plate which is spaced from the case bottom, a pair of cups, each adapted for the reception of an article, depending through the plate into the space therebelow, means whereby one cup is connected fast to the plate and the other is removably supported thereby, and movable closure means for the space below the plate adapted at times to release loose material therefrom, substantially as described.

3. A vanity case having a compartment enclosed in part by a plate which provides a mounting for two depending pockets each for the reception of an intended article, means whereby one pocket may be removed to afford access to the compartment, a lid pivoted to the plate and forming a closure for one pocket, there being a finger projected laterally from the lid to overhang the other pocket when the lid is in one position, and when in another position to be removed therefrom, the finger serving when in overhanging relation to the other pocket to retain an article therewithin, and sifter means for permitting discharge of loose material from the compartment, substantially as described.

4. A vanity case together with a cover therefor, the case having a bottom and side walls, and the cover also having side walls in engagement with those of the case, a plate mounted in the case in spaced relation to its bottom, three pockets depending from the plate into the space therebelow, and a lid slidably mounted on the plate adapted when in one position to form a closure for one pocket, and a partial closure for another, and when in a second position to form a partial closure for the first pocket, and a complete closure for the third pocket, substantially as described.

5. A vanity case having a bottom and provided with a mounting for a plate which extends transversely in spaced relation to the case bottom whereby to provide a compartment for the reception of loose material, a pair of cups depending into the compartment supported by the plate in adjacent relation, and a lid pivoted to the plate between the two cups and adapted for limited sliding movement over the plate, there being a plurality of openings through the lid and plate adapted when the former is in one position to register with each other, and when in another position to misalign whereby the lid serves as a closure for the compartment, substantially as described.
